ROY D. CONWAY, OF CHATHAM, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

1,265,751.

Specification of Letters Patent. Patented May 14, 1918.

Application filed July 9, 1917. Serial No. 179,416.

To all whom it may concern:

Be it known that I, Roy D. Conway, a citizen of the United States, residing at Chatham, in the county of Morris and State 5 of New Jersey, have invented certain and useful Improvements in Signaling Systems, of which the following is a full, clear, concise, and exact description.

This invention relates to signaling systems, and more specifically to signaling systems which are particularly applicable to signaling on composite telegraph and telephone circuits.

In certain telephone systems, particularly 15 those in which both telegraph and telephone circuits are combined, it is desirable to use, for signaling purposes, currents of different frequencies.

Especially in composite telegraph and 20 telephone systems, it is desirable to use high frequency currents of approximately 133 cycles per second for the purpose of operating a signal in connection with the telephone service without interfering with the operation of the telegraph service. Since the 25 standard type of signal used on telephone lines is arranged to respond only to a current of a much lower frequency, it is necessary to provide some means for translating the high frequency current into a current of 30 such low frequency as will properly operate the telephone signal. The signaling current ordinarily used in connection with telephone service has a low frequency, and, in order to 35 eliminate the necessity of the operator using a special source of signaling current in connection with the composite lines only, it is desirable to provide means whereby the low frequency current is translated into a high 40 frequency current suitable for transmission over such lines without interfering with the telegraph service.

In signaling systems now in use in connection with composited telegraph and telephone lines, considerable difficulty has been experienced due to the improper operation of the apparatus caused by the signaling currents used for the telegraph service, or by the actuation of the switch hooks on the 45 connected telephone lines. Due to these conditions as well as to the desirability of employing the same signaling equipment in connection with telephone lines of various 50 lengths, it has been necessary in the past to 55 provide a highly accurate adjustment of the

actuating parts of the apparatus involved in order to prevent the improper operation of the apparatus. Such a refinement in adjustment has been extremely difficult to obtain as well as to maintain when once secured and has necessarily limited the variation of the lengths of line over which the signaling might be properly accomplished.

The object of the present invention is to provide an arrangement which overcomes 60 these difficulties and one which is simple, inexpensive and may be readily applied to systems of this character without interfering with the existing apparatus.

To obtain this object, in accordance with 70 one feature of this invention, a high impedance polarized relay with a vibratory armature is bridged across the conductors of a composited telephone line at a point intermediate the ends of the line. This relay is 75 responsive to a signaling current of any frequency which may be applied at either end of the line and selectively controls local circuits containing tuned relays responsive to particular frequencies, for connecting to one 80 end of the line a source of signaling current separate from that which is impressed on the other end of the line.

These and other features, not specifically 85 mentioned above, will more clearly appear from the following specification and the annexed drawing in which the figure shows diagrammatically, sufficient of one end of a composited telephone line to illustrate the invention.

In the accompanying drawing the jack 1 and the drop 2 represent the terminus of a telephone line which is composited. Although not shown on the drawing, since it is not essential to the proper understanding 95 of the invention it is understood that the usual operator's cord circuit equipped with the ordinary ringing device is available for connection with jack 1. The line conductors 15 and 16 may be assumed as connected 100 with the line side of a regular composite circuit (not shown), which is associated with the telephone line under consideration and at the distant end of the telephone line (also not shown) there may be an arrangement similar to that shown in the drawing.

It is thought that the invention may be more clearly understood from a description of the operation of the signaling system.

Assume that the operator at the station at 110

which the jack and drop are located desires to operate the telephone signal at the other end of the composited line. The operator inserts the plug of the usual cord circuit in the jack 1 and operates the ordinary ringing key provided in the cord circuit so that signaling current of the usual frequency of $16\frac{2}{3}$ cycles per second is impressed upon the line. This current will flow through the condenser 3, and the winding of relay 4. Since relay 4 is so designed that it will respond to current of any frequency, the armature thereof will vibrate in synchronism with the source of the signaling current being impressed upon the line, which, in this case, has been assumed to be $16\frac{2}{3}$ cycles per second. When the armature makes contact with contact 5, two circuits are completed, one of which proceeds from battery 9, winding of relay 8, resistance 7, armature of relay 4, contact 5, resistance 6 to ground. The second circuit extends from battery 21, winding of relay 20 to the terminal of resistance 7, where it joins the first circuit. When the armature is in this position, it will be assumed that the direction of flow of the current is from batteries 9 and 21, through relays 8 and 20, respectively, and resistance 7. Correspondingly, when the armature of relay 4 makes contact with contact 18, two other circuits are completed, the first of which may be traced from ground, battery 21, winding of relay 20, resistance 7, armature of relay 4, contact 18, resistance 17, battery 19. The second circuit may be traced from ground, battery 9, winding of relay 8, to the terminal of resistance 7, where it joins the first circuit. It will be noted that inasmuch as battery 19 is one having approximately twice the voltage of either battery 9 or 21, and, due to the differential series relation existing between battery 19 and each of batteries 9 and 21, when the armature of relay 4 is in contact with contact 18, the direction of current flow through relays 8 and 20 and resistance 7 in the two circuits just traced, will be opposite to that of the current which will flow through the same relays and resistance when the armature of relay 4 is in contact with contact 5.

These continuous reversals of direction of flow of the current through the resistance 7 and the relays 8 and 20, produce alternating current effects, which are in synchronism with the frequency of the current which is operating relay 4, which, in this case, has been assumed to be $16\frac{2}{3}$ cycles per second. Alternating current relay 8, which is tuned to respond to currents having such a frequency, will, therefore, be operated while alternating current relay 20, which is tuned to operate only at a current having a frequency of 133 cycles per second, will remain inactive.

The operation of relay 8 completes a circuit from battery 11, winding of relay 10, contact and armature of relay 8, to ground. Relay 10 is thereby operated and completes a circuit from battery 11, armature and contact of relay 10, windings of relays 12 and 14, to ground. Relays 12 and 14 are operated over this circuit. Relay 12 closes a circuit, including a source of signaling current 13, and the primary of the transformer 25. In operating, relay 14 connects the terminals of the secondary of the transformer 25 to the outgoing telephone line, represented by conductors 15 and 16, and disconnects therefrom the remainder of the line apparatus at the calling station. Since the source of signaling current in this case is arranged to furnish current at 133 cycles per second, a current having such a frequency is impressed upon line conductors 15 and 16, and transmitted over the remainder of the composite circuit to the station at the distant end, both of which portions of the completed connection have been omitted from the drawing for the sake of clearness. When the operator disconnects the source of signaling current from the line, all of the apparatus will return to its normal position.

In the case of an incoming call, let it be assumed that, at the distant office, current 95 having a frequency of 133 cycles per second is being transmitted over the line and is impressed upon line conductors 15 and 16. Such current will operate relay 4 in the same manner as before except that the armature 100 will vibrate in synchronism with the high frequency current. The actuation of the armature of relay 4 will close circuits similar to those completed in the case of an outgoing signal, but the alternating current effects 105 produced through the relays 8 and 20 and the resistance 7 also correspond with the higher frequency, and will, therefore, operate relay 20, while relay 8 remains inactive. The operation of relay 20 completes a 110 circuit from battery 11, through winding of relay 22, through the armature and contact of relay 20 to ground. In operating, relay 22 closes a circuit from battery 11, armature and contact of relay 22, the winding of relay 23 to ground. Relay 23 operates, and thereby connects a source of signaling current, having a frequency of $16\frac{2}{3}$ cycles per second, across the tip and ring of the line, which current operates the drop 2. The remainder of the line circuit is also disconnected by the operation of relay 23. When the application of the high frequency current to the incoming line is discontinued, all apparatus returns to normal, as in the previous case.

What is claimed is:

1. In a signaling system, a line circuit, means connected to said line circuit at an intermediate point thereof responsive to a 130

6. In a signaling system, a line circuit, means connected to said line circuit at an intermediate point thereof responsive to a signaling current of any frequency impressed upon either end of said line, means responsive to a definite frequency of signaling current of any frequency impressed on either end of said line circuit at an intermediate point thereof responsive to a signaling current of any frequency impressed upon either end of said line, means responsive to a definite frequency of signaling current impressed on either end of said line selectively controlled by said first mentioned means, and means controlled by said last mentioned means for connecting a separate source of signaling current to the other end of said line. 70
10. 2. In a signaling system, a line circuit, a polarized relay connected to said line at an intermediate point and responsive to a periodically varying current at any frequency when impressed on either end of said line, 75 means controlled by said polarized relay for producing in local circuits a current in synchronism with that impressed upon the line, and means included in said local circuits operable in response to a certain definite frequency for connecting a source of signaling current of a different frequency to the other end of the line. 80
15. 3. In a signaling system, a line circuit, a polarized relay bridged across said line at an intermediate point thereof and responsive to currents of any frequency when impressed on either end of said line, a plurality of tuned relays selectively controlled by said polarized relay and each responsive to a particular frequency of current when current of the corresponding frequency is impressed on said line, and means individual to and controlled by each of said tuned relays for connecting to one end of said line a 85 signaling current having a frequency differing from that of the signaling current impressed on the other end of the said line. 90
20. 4. In a signaling system, a line circuit, means connected to said line at an intermediate point thereof responsive to a signaling current of any frequency impressed on either end of said line, means responsive to a definite frequency of signaling current impressed on either end of said line selectively controlled by said first mentioned means, and means controlled by said last mentioned means for interrupting the flow of said signaling current at said intermediate point of said line and for connecting a separate source of signaling current to the other end of said line. 95
25. 5. In a signaling system, a line circuit, means connected to said line circuit at an intermediate point thereof responsive to a signaling current of any frequency impressed on either end of said line, means responsive to a definite frequency of signaling current impressed on either end of said line selectively controlled by said first mentioned means, and means controlled by said last mentioned means for connecting a separate source of signaling current to the other end of the line and for preventing the transmission of the first mentioned signaling current to the other end of said line. 100
30. 6. In a signaling system, a line circuit, a polarized relay connected to said line at an intermediate point thereof responsive to a signaling current of any frequency impressed on either end of said line, means responsive to a definite frequency of signaling current impressed on either end of said line selectively controlled by said first mentioned means, and means controlled by said last mentioned means for connecting the separate source of signaling current to the other end of the line and for preventing the transmission of the signaling current past the first mentioned means. 105
35. 7. In a signaling system, a line circuit, switching means responsive to a periodically varying current of any frequency impressed on either end of said line, two local circuits independent of said line circuit, means controlled by said switching means for producing a current in said local circuits in synchronism with the current impressed upon the line, and means controlled by current in said local circuits for impressing on the opposite end of said line signaling current having a different frequency. 110
40. 8. In a signaling system, a line circuit, a polarized relay responsive to periodically varying currents of any frequency connected to the line circuit at an intermediate point thereof, means controlled by said polarized relay for producing in local circuits a current in synchronism with the current in the polarized relay, and means controlled by current in said local circuits for selecting and connecting to the line signaling current having a predetermined frequency differing therefrom. 115
45. 9. In a signaling system, a line circuit, two local circuits each arranged to connect one of two sources of periodically varying currents of different frequencies to said line, switching means connected to said line at an intermediate point thereof responsive to a current of any frequency, and means controlled by said switching means for selectively operating apparatus in one of said local circuits when a frequency corresponding to that controlled by apparatus in the other of said local circuits is impressed on either end of the line. 120
50. 10. In a signaling system, a line circuit, a polarized relay bridged across said line at an intermediate point thereof and having an armature adapted to vibrate in synchronism with the frequency of any signaling current impressed on either end of said line, a tuned relay for each operative position of said armature responsive to one particular current frequency, local circuits arranged to be closed by said polarized relay for operating each of said tuned relays when a signaling current having its associated frequency is impressed on one end of said line, a plurality of sources of signaling current 125
55. 65. 11. In a signaling system, a line circuit, a polarized relay connected to said line at an intermediate point thereof responsive to a signaling current of any frequency impressed on either end of said line, means responsive to a definite frequency of signaling current impressed on either end of said line selectively controlled by said first mentioned means, and means controlled by said last mentioned means for connecting a separate source of signaling current to the other end of the line and for preventing the transmission of the first mentioned signaling current to the other end of said line. 130

- having different frequencies corresponding to those on which the tuned relays are responsive, and a plurality of relays controlled by each of said tuned relays for connecting to one end of said line one of said sources of signaling current when a signaling current having a frequency to which the tuned relay is responsive is impressed upon the other end of said line.
11. In a signaling system, a line circuit, a polarized relay bridged across said line at an intermediate point thereof adapted to vibrate in synchronism with the signaling current of any frequency connected to either end of said line and having an armature with two operative positions, two local circuits arranged to close when said armature is in either of its operative positions, a tuned relay responsive to a particular frequency of current only and a resistance connected in each of said local circuits, two sources of current having different voltages arranged to be included in said local circuits upon the operation of said armature to produce in both of said local circuits a periodically varying current having a frequency in synchronism with the signaling current operating said polarized relay, two sources of periodically varying signaling currents having different frequencies, and a plurality of relays controlled by each of said tuned relays for connecting to one end of said line one of said sources of periodically varying signaling current when a signaling current having a frequency corresponding to that of the other of said sources of periodically varying current is impressed upon the other end of said line.
12. In a signaling system, a line circuit, a polarized relay bridged across said line circuit at an intermediate point thereof and having an armature with two operative positions and arranged to vibrate in synchronism with a signaling current of any frequency connected to either end of said line, 45 two local circuits arranged to be closed when said armature is in either of its operative positions, two sources of current having different voltages arranged to be included in said local circuits individually or in differential 50 series relation upon the operation of said armature to produce in both of the said local circuits a periodically varying current corresponding in frequency with the signaling current impressed upon the line, a tuned 55 relay responsive to only one frequency of current and a resistance included in each of said local circuits, a source of periodically varying signaling current corresponding in frequency with that to which each of said 60 tuned relays is responsive, and a plurality of relays controlled by each of said tuned relays for connecting to one end of said line one of said sources of periodically varying current when the relay responds to a current corresponding in frequency with that of the other said source of periodically varying current.
- In witness whereof, I hereunto subscribe my name this 3rd day of July, A. D., 1917. 70
- ROY D. CONWAY.
